UNITED STATES PATENT OFFICE.

AMOS READ, OF JAMESTOWN, NEW YORK.

TRUSS-PAD.

SPECIFICATION forming part of Letters Patent No. 234,333, dated November 9, 1880.

Application filed February 6, 1880.

To all whom it may concern:

Be it known that I, AMOS READ, of Jamestown, in the county of Chautauqua and State of New York, have invented certain new and useful Improvements in Truss-Pads; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of my invention is to provide a simple, cheap, and efficient truss-pad for holding a hernia or rupture, and effecting a cure for the same, and one not liable to the objections of those in common use; and it consists in making the pad of one-half of a common clam-shell with suitable filling material and devices for holding the same, as will be more readily understood by the following description and accompanying drawings, in which—

Figure 1 is a side elevation. Fig. 2 is a side elevation with belt attached. Fig. 3 is a plan view of edge.

The objection found to truss-pads as heretofore constructed is, that many of them are held in position by means of springs, and thus cause constant pressure on the body, and so irritate the skin as to cause soreness and prevent them being worn nights, when most needed to effect a cure.

Those known as "belt-pads" are smooth and slip easily on the body, so that any sudden jar is liable to displace them so the intestine works out at the side, and not only impedes the cure, but many times prevents it entirely.

To overcome these objections I take a common clam-shell with its natural ridges retained, as shown in the drawings, Figs. 1 and 3, and fill it with plaster-of-paris, B, and before it hardens I embed into it pins or studs C, which, when it hardens, securely holds them,

and they project enough above the surface of the pad to attach the belt, as shown in Fig. 2.

The surface of the plaster-of-paris is made oval and highest at the center, so as to have the belt when drawn around the patient press hardest on this point, the outside of the clam-shell being placed directly against the rupture and held there by the belt with suitable side stays for keeping it in position.

The natural ridges on the outside of the clam-shell pressing against the rupture prevents the intestine from working out, and at the same time is much cooler than a smooth pad and so comfortable that they can be worn constantly or till the cure is effected.

I make a right or left pad from the corresponding sides of the clam-shell, and the different-size shells give any desired size of pad. So it will be readily seen that they can be made at much less cost than others, besides being more durable and efficient.

I have sometimes used the shell and put wire studs across it to attach the belt thereto, and sometimes have inserted a coiled spring into the shell and let the belt pass over that, and have also used other devices for holding the clam-shell pad for this purpose, but find the plaster-of-paris filling and studs more durable, besides being cheaper and giving a more desirable shape to the pad.

As I have used and found the different devices mentioned for holding the clam-shell will answer, I do not wish to be strictly confined to the plaster-of-paris filling.

I claim—

In a truss-pad, the combination of the clam-shell with its natural ridges retained, and the inner filling of plaster-of-paris or its equivalent, carrying suitable pins or studs for attachment to a belt, all arranged as described, and for the purpose set forth.
